3,163,289 PACKAGE

Harry P. Laffkas, Addison, and Thomas H. Ward, Corning, N.Y., assignors to Corning Glass Works, Corning, N.Y., a corporation of New York
Filed Sept. 10, 1962, Ser. No. 222,269
3 Claims. (Cl. 206—65)

This invention relates to a two-part package useful for containing a plurality of articles.

It is an object of the invention to provide a package which can be used without alteration to hold tightly articles of various sizes.

Another object is to provide a package comprising two identical, interchangeable parts.

Another object is to provide a package capable of cushioning frangible articles contained therein against mechanical shock.

These and other objects, which will be apparent from the description, are accomplished by the provision of a package comprising two identical parts, each part defining a cavity and having a sidewall provided with a flange contiguous with a surface of the sidewall and having article-holding means within each cavity.

The invention will be described with reference to the accompanying drawing, in which:

FIG. 1 is a plan view looking into the cavity of one of the identical parts of the package,

FIG. 2 is a sectional view taken on line II—II of FIG. 1,

FIG. 3 is a sectional view taken on line III—III of FIG. 1,

FIG. 4 is a sectional view taken on line IV—IV of FIG. 1,

FIG. 5 is a perspective view of the two parts of the package prior to closing the package,

FIG. 6 is a sectional view of an assembled package having glass test tubes packed therein, and

FIG. 7 is a sectional view taken along a plane perpendicular to that of FIG. 6 and showing test tubes packed with their axes perpendicular to those shown in FIG. 6.

As illustrated in the drawing, the package of the present invention comprises two identical parts 10 formed of foamed polystyrene plastic. Each part has, within its cavity defined by sidewall 11 and bottom 17, two pairs of article-supporting ribs. Ribs 13 of one pair are respectively perpendicular to ribs 14 of the other pair. Ribs 13 and 14 are provided respectively with arcuate depressions 15 and 16 for rigidly holding test tubes T-1 or T-2, as shown in FIGS. 6 and 7.

Each part 10 is provided with flange 12, which telescopes into the other part when the two parts are assembled to form a package, as shown in FIGS. 5 and 6. Flanges 12 extend around half of sidewalls 11, and thus a complete enclosure is formed for articles within the package even when the package is only partially closed. Depressions 15 and 16 have differing diameters to facilitate holding articles of differing sizes, only one set of depressions being used at any one time. In addition, articles having diameters larger than either tubes T-1 or tubes T-2 of FIGS. 6 and 7 can be packaged, and although the sidewalls of the respective parts will not meet, the articles will nevertheless be enclosed by the flanges. In such cases, although the curvatures of the depressions will not conform precisely to those of the packaged articles, the articles will nevertheless be held immovable.

It will be apparent that the illustrated package may be modified while retaining the advantages thereof. Ribs 13 and 14 and depressions 15 and 16 may be modified or replaced by other structures conforming to the shapes of other articles to be packaged or may be absent alto-

2

gether. Flanges 12 need not be formed on the inner surfaces of sidewalls 11 but may be adjacent to the outer surfaces thereof. In addition, they need not extend along precisely half of the sidewalls as in the illustrated embodiment, nor need each part have a single continuous flange. The parts will be interchangeable and will telescope with one another if each sidewall mating edge, such as edge 18 of FIG. 2, is symmetric about a line passing through that mating edge and if at the same time all flange portions of each respective part are arranged about and parallel to a single straight axis and no two flange portions of either part are contiguous to any two mating edge points which are located symmetrically with respect to said line. In the illustrated embodiment, the said line of symmetry of mating edge 18 is line A—A of FIG. 1, and the said axis is line B—B of FIG. 5, which is perpendicular to base 17. Although the most convenient form of flange is that illustrated in the drawing, other forms, either continuous or discontinuous, which satisfy the above conditions will accomplish the objects of the invention. Mating edges 18 need not each lie in a plane as in the illustrated embodiment as long as the above condition of symmetry is satisfied.

The illustrated package has been constructed of foamed polystyrene plastic, since this material is light and easily molded and cushions frangible articles against mechanical shock. It will be understood that the package may be constructed of other foamed plastics or of any conventional packaging material and that the respective parts of the package may be assembled from components rather than molded as single structures. The parts need not be shaped as illustrated but may have any shape dictated by the shapes of the articles to be packed.

Accordingly, it is intended that the present invention be limited not by the description given above as that of a single embodiment of the invention, but rather only by the scope of the appended claims.

What is claimed is:

1. A package comprising two identical telescoping parts, each of said parts comprising a bottom and a side wall, each of said side walls terminating in substantially identical mating edges, each said mating edge being symmetric about a line passing through said edge, each of said side walls having a flange contiguous thereto and extending outwardly away from said bottom, said flange of each said part telescoping with said side wall of the other said part, and within each said part two sets of ribs, each of said sets comprising at least two parallel ribs having article-supporting depressions therein, the ribs of one set being respectively perpendicular to the ribs of the other set, said depressions of each set of ribs being substantially identical to the remaining depressions of the same set but different from those of the other set.

2. A package according to claim 1 in which said flanges are contiguous to the inner surfaces of said side walls.

3. A package according to claim 2 in which each said flange is confined to one side of said line of symmetry.
